UNLOADING MECHANISM

Dwight A. Johnston, Youngstown, Ohio, assignor
to McKay Machine Company, Youngstown,
Ohio, a corporation of Ohio

Application January 9, 1939, Serial No. 249,879

12 Claims. (Cl. 153—61)

The present invention relates to the art of forming metal articles and more particularly to novel method and apparatus for removing bent or curved stock from bending or forming machines and the like. Heretofore, the expeditious removal of the formed article from bending, rim rolling and other similar machines has presented difficulties since the inherent strength and resiliency of the formed article resists separation of the same from parts of the machine about which it may have become encircled. Thus the productive capacity of machines of the kind indicated has heretofore been limited and it is, accordingly, the primary object of the invention to provide a mechanism whereby the formed articles may be quickly removed from such machines.

A further object of the invention is the provision of apparatus for the purpose stated which is automatic in its operation and which consists of relatively few simply constructed parts whereby the same is economical to construct and dependable in operation.

The above and other objects and advantages of the invention will become apparent from a consideration of the accompanying drawings and the following detailed description of a representative adaptation of the principles of the invention. For illustration purposes, the invention is shown as applied to a rim bending machine the function of which is to convert straight lengths of the rim stock into looped forms preparatory to welding and other fabrication processes although it should become obvious that the invention is adaptable to other specific uses.

In the drawings:

Figure 1 is an end view of a rim bending machine embodying the principles of the invention;

Figure 2 is a side elevation of the machine of

Figure 1;

Figure 3 is an enlarged sectional view taken along the line 3—3 of Figure 1; and

Figure 4 is an enlarged sectional view of a structural feature of the machine.

The rim forming machine consists essentially of three bending rolls arranged in pyramid formation, the lower two rolls 10 being fixed while the upper roll 11 is vertically adjustable by the screws 12. The inner ends of the rolls are rotatably supported in bearings supported by the gear case 13 while the outer ends thereof are journaled in the outboard housing 14. The rolls are driven by the motor 15 through a drive 16 and suitable gearing (not shown) housed within the case 13. The various component parts of the machine are

assembled on the base 17 and by referring to Figures 2 and 3 it can be seen that as the stock 20 is fed into the machine and between the upper and lower bending rolls, 11 and 10, respectively, it will be bent into a looped form indicated at 21. 5 In accordance with usual practice suitable operating means 23-24 is provided to raise and lower the screws 12 whereby the relative vertical position of the upper roll and consequently the radius of curvature of the looped form may be varied. 10 The stock is guided into the bending rolls by the guide rolls 23 and the machine may include marking or stencil and anvil rolls 26 and 27, respectively.

Each of the lower bending rolls 10 consists of 15 a pair of spaced sleeves 30 keyed on a shaft 31. Interposed between the sleeves on each of the shafts 31 are the sprockets 32 at least one of which is keyed to its carrying shaft. The outer diameter of the sprockets 32 is less than the 20 diameter of the sleeves 31 to provide space within the general peripheral contour of the rolls for an endless link chain 33 which passes over both sprockets 32. A series of spaced dogs 34 are carried on the chain 33, each being pivotally attached thereto at its leading end by the pin 35 and being provided with suitable means (not shown) biasing its trailing end to outer position. Dogs 34 are provided with outwardly extending lugs 36 and the various parts involved are so 30 proportioned that with the dogs in their inner retracted positions the lugs are substantially within the general outer periphery of the chain. In outer position of the dogs, the lugs 36 extend 35 outwardly of the chain.

Encircling a portion of the upper bending roll 11 and mounted in close proximity thereto is the accurately shaped member 38 which is adapted to rotate about the axis of the roll. For the latter purpose, the member 38 is carried by sleeves 39 40 (see Figure 4) rotatably mounted on the shaft 11' of the upper bending roll 11. One of the sleeves 38, preferably the one adjacent the gear case 13 is provided with a sprocket 39' about which is looped the link chain 40. The lowermost reach of chain 40 passes over an idler sprocket 41 and has its end attached to a resilient coil spring 42. The other portion of chain 40 passes over a second idler sprocket 43 and has its end attached to the piston rod 45 of an air 50 or hydraulic cylinder 44.

Compressed air from a suitable source 46 is supplied to cylinder 44 through the three way valve 47 and conduit 48. Valve 47 is controlled by a solenoid 50 which when energized operates 55

- to connect source 46 and the conduit 48, the valve being so constructed that upon deenergization of solenoid 50, the conduit 48 is connected with the outlet 49. Energization of solenoid 50 from line 54 is controlled by switch 51 which in turn is actuated by a lever pivotally mounted on the frame of the machine and carrying at its upper end a roller 53 which is adapted to be engaged by the stock 20 passing through the machine.
- 10 When stock 20 is engaging roller 53, lever 52 is in its counterclockwise position, as viewed in Figure 3, and the switch 51 is open. As the end of the stock leaves roller 53, the blade of switch 51 moves to closed position and the solenoid 50 is energized through line 54, switch 51, conductor 56, solenoid 50, conductor 57, normally closed switch 55 and back to line 54.

Extending radially outward from the central portion of and preferably integral with the member 38 is the flap 58 the purpose of which is to form an abutment for the leading edge of the stock piece 20 after the same has been bent into loop form by the bending rolls previously described.

- 25 In operation, the stock pieces 20 are guided into the machine as described above and as the roller 53 is engaged and arm 52 rotated counterclockwise, switch 51 is opened, deenergizing solenoid 50 and releasing pressure from within cylinder 44 thereby enabling spring 42 to contract and to consequently move the chain over sprockets 39', 41 and 43. Resultant rotation of sprocket 39' moves the member 38 and flap 58 to the position shown in full lines in Figure 3. As 30 the stock passes between the bending rolls 10-11 and over the chain 33, the lugs 36 of the pivoted dogs 34 will be maintained in resilient engagement with the under surface of the stock. When, however, the end of the stock piece reaches the 35 first of the lower bending rolls, the lugs 36, because of the outward biasing of the dogs 34, will move outwardly and engage the end of the piece. In the meantime, the piece will have passed over roller 53 and cylinder 44 through chain 40 will 40 have either moved the flap 58 to the position shown in dotted lines or will be tending to move the flap to such position. As the bending process is completed the trailing edge of the stock piece will be engaged by one of the lugs 36 and the 45 trailing end ejected from the space between the rolls. Upon the release of the stock piece from between the rolls, the flap 58 will move rapidly upward, if it is not already in upper position, thereby springing the looped form from the upper bending roll and consequently away from the machine. The operation is such that forces are 50 exerted on both ends of the looped stock piece to spring the same over and away from the roll about which it may have become resiliently engaged upon completion of the bending or forming process.

The above specifically described embodiment of the invention should be considered as illustrative only as obviously many changes may be made therein without departing from the spirit or scope of the invention, the extent of which is indicated in the appended claims.

What I claim is:

1. In combination with a bending machine 70 having two anvil rolls and a bending roll, means to eject completed forms from said machine comprising pass aligned recesses in the working surfaces of the anvil rolls, a sprocket in each of said recesses and rotatable with said rolls, a link 75 chain connecting said sprockets, a plurality of

spaced dogs pivotally mounted on said chain and each provided with an outwardly extending lug, said dogs being normally biased to positions outwardly of the contour of said chain and rolls, a flap rotatable about the axis of the bending roll 5 and adapted to form an abutment for the leading end of the stock piece being bent, means operable upon engagement with the stock piece to retain said flap in retracted position, said means being operable upon disengagement with 10 said stock piece to urge said flap toward the material leaving side of the group of said rolls.

2. In combination with a bending machine having two anvil rolls and a bending roll, means 15 to eject completed forms from said machine comprising pass aligned recesses in the working surfaces of the anvil rolls, a sprocket in each of said recesses and rotatable with said rolls, a link chain connecting said sprockets, a plurality of spaced dogs pivotally mounted on said chain and 20 each provided with an outwardly extending lug, said dogs being normally biased to positions outwardly of the contour of said chain and rolls, a flap rotatable about the axis of the bending roll and adapted to form an abutment for the leading end of the stock piece being bent, said flap 25 being carried by a sleeve rotatably mounted on the shaft of said bending roll, a sprocket on said sleeve, a link chain passing over said sprocket and connected at one end with a motor, a spring 30 connecting the other end of said last mentioned chain, and a switch operated by stock passing through said machine in control of said motor.

3. In combination with a bending machine having two anvil rolls and a bending roll, means 35 to eject completed forms from said machine comprising pass aligned recesses in the working surfaces of the anvil rolls, a sprocket in each of said recesses and rotatable with said rolls, a link chain connecting said sprockets, a plurality of spaced 40 dogs pivotally mounted on said chain and each provided with an outwardly extending lug, said dogs being normally biased to positions outwardly of the contour of said chain and rolls, and stop means engageable by the leading ends of said 45 forms to open out the loops in said forms whereby said dogs are operable to spring the forms away from said bending roll.

4. In combination with a bending machine having two anvil rolls and a bending roll, means 50 to eject completed forms which may have become encircled about said bending roll, comprising a flap rotatable about the axis of the bending roll and adapted to form an abutment for the leading end of the stock piece being bent, means 55 to move said flap toward the material leaving side of the group of said rolls, and means operable by stock passing through said machine to control said second mentioned means.

5. In combination with a bending machine 60 having two anvil rolls and a bending roll, means to eject completed forms from said machine comprising means to engage the leading end of the stock piece after the stock has passed through the rolls, means to engage the trailing end of 65 said stock piece as the same is passing between the rolls and means operable in response to the position of said trailing end to move said first mentioned means toward the material leaving side of the group of rolls.

6. In combination with a machine having a stock bending pass, means to eject bent forms from an element of said machine about which the forms may have become encircled comprising a chain adapted to engage the outer surface of 75

moving and changing portions of the stock piece, means carried on the chain to engage the trailing end of the piece, means to engage the leading end of said piece after it has passed through said 5 pass, means to move said leading end engaging means toward the material leaving side of said pass whereby the bent form may be sprung from said element, and means responsive to the position of said trailing end in control of said fourth mentioned means.

7. In combination with a machine having a stock bending pass, means to eject bent forms from an element of said machine about which the forms may have become encircled comprising a chain adapted to engage the outer surface of moving and changing portions of the stock piece, means carried on the chain to engage the trailing end of the piece, means to engage the leading end of said piece after it has passed 10 through said pass, and means to move said last mentioned means toward the material leaving side of said pass whereby the bent form may be sprung from said element.

8. In combination with a machine having a stock bending pass, means to eject bent forms from an element of said machine about which the forms may have become encircled comprising means to engage and propel the trailing end of the stock piece as it issues through the pass, 15 means to engage the leading end of the stock piece after it leaves the pass, means to move said last mentioned means toward the material leaving side of said pass whereby the bent stock piece may be sprung from said element, and means responsive to the position of said trailing end in control of said fourth mentioned means.

9. In combination with a machine having a stock bending pass, means to eject bent forms from an element of said machine about which

the forms may have become encircled comprising means to engage and propel the trailing end of the stock piece as it issues through the pass, means to engage the leading end of the stock piece after it leaves the pass, and means to move 5 said last mentioned means toward the material leaving side of said pass whereby the bent stock piece may be sprung from said element.

10. In combination with a machine having a stock bending pass, means to eject a bent stock piece from an element of the machine about which it may have become encircled comprising a member against which the leading end of the stock piece may abut after it leaves the pass, means to move said member toward the leaving 10 side of said pass, and means responsive to the position of the trailing end of said piece in control of said last mentioned means.

11. In combination with a bending machine having two anvil rolls and a bending roll, means to eject completed forms from said machine comprising pass aligned annular recesses in the working surfaces of said anvil rolls, a stop engageable by the leading ends of said forms as said forms issue through said pass, an endless member 15 entrained over said anvil rolls within said recesses and being provided with means to engage the trailing ends of said forms whereby said trailing ends are positively propelled through said pass.

12. In combination with a bending machine 20 having two anvil rolls and a bending roll, means to eject completed forms from said machine comprising means to engage an edge of said forms tending to move said forms away from said machine, and means responsive to the position of 25 the trailing ends of said forms relative to the pass between said rolls to actuate said edge engaging means.

DWIGHT A. JOHNSTON.
